UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

SIGNAL AND PARKING LAMP.

Application filed November 5, 1921. Serial No. 513,059.

To all whom it may concern:

Be it known that I, JOHN BERG, a citizen of the United States, residing at Chicago, in the county of Cook and State of Illinois, have invented a new and useful Improvement in Signal and Parking Lamps, of which the following is a specification.

This invention relates particularly to a signal and parking lamp for use on motor vehicles; and the primary object is to provide an improved lamp of this character which can be used for signalling purposes when the vehicle is being driven, and can be used for parking purposes when the car is left standing in a public place.

The invention is illustrated, in its preferred embodiment, in the accompanying drawing, in which—

Fig. 1 represents a broken front view of the improved signal and parking lamp; Fig. 2, a vertical sectional view taken as indicated at line 2 of Fig. 1; Fig. 3, a broken sectional view taken as indicated at line 3 of Fig. 2, the reflector being removed; and Fig. 4, a broken view of the reflector.

In the construction illustrated, A represents a casing having a peripheral wall A' and a rearwardly dished rear wall A²; B, a glass bull's-eye mounted in a central perforation with which the wall A² is provided; C, a reflector mounted in the rear portion of the casing; D, an incandescent lamp mounted in the casing in front of said reflector; and E, a lens or glass-plate secured to the front portion of the peripheral wall A' and constituting the front wall of the casing.

In the form illustrated, the casing A has its peripheral portion A' of cylindrical form and has its rear wall A² bowed rearwardly. The casing may be drawn from sheet metal. The rearwardly bowed wall A² is provided with a central perforation 1 thru which the glass bull's-eye B projects. The metal surrounding the opening 1 is struck inwardly to form a narrow flange 1^a which is slightly dished or concaved to accommodate the bull's-eye, that is, the flange 1^a flares or diverges forwardly and is made slightly concave to conform closely to the base portion of the bull's-eye.

The bull's-eye B approximates the form of a half of a solid sphere or cone. It presents a flat base 2, which is however preferably concaved slightly as indicated by the dotted line at 2^a. The periphery of the base

portion of the bull's-eye fits snugly in the socket afforded by the concave flange 1^a.

The flange 1^a is provided at its inner edge with clenching lugs 3 formed integrally with the flange. These clenching lugs extend thru perforations 3^a which are grouped about a central perforation 4 with which the reflector C is provided. The reflector C is dished or bowed rearwardly and has its central portion bearing against the base portion of the bull's-eye. The peripheral portion of the reflector is curved rearwardly as indicated at 5 and bears against an internal shoulder with which the rear portion of the casing A is provided.

It will be understood that the reflector is secured in position by passing the clenching lugs 3 thru the perforations 3^a of the reflector and clenching them against the front face of the reflector.

The incandescent lamp bulb D is mounted in a socket D' which is secured to the peripheral wall of the casing. The socket D' is a tubular member which extends thru a perforation in the peripheral wall of the casing, said peripheral wall having the metal sheared at said opening and struck inwardly to provide integral lugs 6 which are secured, by rivets 6^a, to the socket D'. The socket D' is suitably formed to receive an electric connector which is attached to conductors forming a part of the electric circuit.

The glass disk E is preferably provided on its rear surface with small prisms 7. These may be molded in the glass in forming the disk. The front face of the glass of the disk 7 preferably is provided with a word adapted to convey a signal or warning a driver in the rear. In the illustration given, the word "Stop" is used. The letters 95 of this word (two of which are shown) are designated 7^a. These letters are preferably raised characters formed integrally with the front surface of the disk 7. In addition, a suitable design 7^b is formed in relief on the 100 front face of the disk 7. The sunken face 7^c of the disk 7 is preferably coated with black enamel, or some opaque substance, so that the word "Stop" and the design 7^b alone remain transparent, the rear surface of the 105 disk being corrugated or prisms, however, which serves to diffuse the light which passes thru the letters of the word "Stop" and thru the raised design portions 7^a, so that no glare will result.

The bottom portion of the casing is equipped with a supporting standard 9 which has a base portion 9^a which is curved to conform to the rear fender of a car. The 5 lamp casing may be mounted upon the rear fender with the glass disk 7 exposed rearwardly of the machine.

In the use of the improved device, the lamp bulb is connected with an electric circuit which is controlled by a suitable circuit-controlling device. This circuit-controlling device, or switch, may, in turn, be controlled by the foot-brake and the emergency brake levers of the automobile. Thus, when the 10 driver of the automobile brings the vehicle to a stop, or turns a corner, the lamp is automatically lighted, as a result of the movement of the braking mechanism, which closes the electric circuit. For parking purposes, 15 the emergency lever may be set, thus closing the electric circuit and maintaining it in closed condition. When the lamp is thus used as a parking lamp, the signal "Stop" is displayed at the rear of the machine, while 20 the white light is thrown thru the bull's-eye B toward the front of the machine. Usually, the lamp is mounted on the left-hand rear fender, so that the light thrown thru the bull's-eye B lights up the left side of the 25 machine. As the white light can be seen from the front, the ordinary lamps of the machine may be turned off, if desired.

The construction described is simple, moderate in cost, and highly effective for its 30 purpose.

The foregoing detailed description has been given for clearness of understanding only, and no unnecessary limitations should be understood therefrom, but the appended 35

claims should be construed as broadly as permissible in view of the prior art.

What I regard as new, and desire to secure by Letters Patent, is—

1. In a signal and parking lamp, the combination of a casing having a peripheral wall and a rear wall, said rear wall having a perforation therein with an inwardly flaring flange at said perforation, affording a socket, said flange being equipped with clenching lugs, a bull's-eye projecting thru 50 said perforation and having its base portion seated in said socket, a reflector provided with a perforation registering with said bull's-eye, said clenching lugs extending thru perforations in said reflector and 55 clenched on the front face of the reflector, an incandescent lamp-bulb mounted in said casing in front of said reflector, and a glass front secured to the front portion of said peripheral wall and provided with signal 60 characters.

2. In a signal and parking lamp, the combination of a casing comprising a cylindrical wall and a rearwardly bowed rear wall which is provided with a central perforation and with an inturned flange at said perforation, a bull's-eye seated in the socket afforded by said flange, a reflector having its central portion bearing against the base of said bull's-eye, clenching lugs on said flange 65 extending thru perforations in said reflector, a socket carried by the peripheral wall of said casing, an incandescent light bulb mounted in said socket, and a glass front secured to the front portion of said peripheral wall and provided with signal characters. 70 75

JOHN BERG.
